The ornamental design for a biochemical analyzer, as shown and described.

DESCRIPTION

FIG. 1 is a front view of a biochemical analyzer, showing my new design;

FIG. 2 is a top view thereof;

FIG. 3 is a right side view thereof;

FIG. 4 is a left side view thereof;

FIG. 5 is a top, front and right side perspective view thereof; and,

FIG. 6 is a top, front and left side perspective view thereof. The rear and bottom views are not shown and form no part of the claimed design.
